(57) **CLAIM**

The ornamental design for a display screen with graphical user interface, as shown and described.

DESCRIPTION

FIG. 1 is a front view of a display screen with graphical user interface showing the design.

FIG. 2 is another view in accordance with an embodiment. FIG. 3 is another view in accordance with an embodiment; and,

FIG. 4 is another view in accordance with an embodiment. The dash-dot broken lines showing an electronic device illustrate environmental subject matter, whereas the broken lines showing a display screen and elements of the graphical user interface illustrate portions of the article. No subject matter depicted in broken lines form part of the claimed design.

1 Claim, 4 Drawing Sheets
